(57) **CLAIM**

The ornamental design for the croquet stake, as shown and described.

DESCRIPTION

FIG. 1 is a perspective view of the front of the croquet stake; FIG. 2 is a front plan view thereof;

FIG. 3 is a bottom plan view shown on an enlarged scale; and,

FIG. 4 is a top plan view thereof.

The portion shown in broken lines is for illustrative purposes only and forms no part of the claimed design.
